UNITED STATES PATENT OFFICE.

CHARLES C. TOMKINSON, OF PLAINFIELD, NEW JERSEY, ASSIGNOR TO J. EDWARD OGDEN, OF MOUNTAINVILLE, NEW YORK.

REVERSIBLE LOCK FOR HANGAR-DOORS.

1,278,258.

Specification of Letters Patent. Patented Sept. 10, 1918.

Application filed October 19, 1917. Serial No. 197,431.

To all whom it may concern:

Be it known that I, CHARLES C. TOMKINSON, a citizen of the United States, and a resident of Plainfield, county of Union, and

5 State of New Jersey, have invented certain new and useful Improvements in Reversible Locks for Hangar-Doors, of which the following is a specification, reference being had to the accompanying drawings, forming

10 a part thereof.

My invention relates to improvements in longitudinally movable doors, and its object is to provide a mechanism for holding such doors against movement in both directions or against movement in one direction or the other. More particularly it relates to a mechanism applied to a pair of such doors movable in a common plane which is so arranged that both of said doors

20 may be locked against movement in either direction, and that when released to move in either direction they are locked against movement in the opposite direction.

A further object of this invention is to 25 combine such a locking mechanism with apparatus for moving the doors in the desired direction. A still further object is to provide a simple device for controlling both the locking mechanism and the doors moving apparatus.

In order that my invention may be thoroughly understood, I will now proceed to describe the same in the following specification, and then point out the novel features

30 thereof in appended claim.

Referring to the drawings:

Figure 1 is a front elevation of a hanger with a pair of doors provided with mechanism which embodies this invention.

40 Fig. 2 is a front elevation of a part of one of the doors on a larger scale with my invention applied thereto.

Fig. 3 is a sectional end elevation of the parts shown in Fig. 2.

45 Fig. 4 is a sectional end elevation of the control lever and connected parts.

Fig. 5 is a plan view of certain of the parts shown in Figs. 2 and 3.

50 Fig. 6 is a diagrammatic view of certain electrical and mechanical connections between the doors and an electric winch.

Like characters are designated by corresponding parts in all the figures.

55 10 designates a building construction

which in this case is a hangar for dirigible

balloons. 11 designates tracks or rails laid across the front of this building, and 12 are overhead guides supported by the building above and parallel with the tracks 11.

The doors are designated by 13 and 14. 60 These are supported upon the journals 15 of flanged wheels 16 on the tracks 11. 17—17 are wheels mounted on vertical shafts projecting downwardly from the bottom of the door structures and bearing upon 65 the inner surfaces of the rails 11. 18—18 are similar wheels mounted on shafts projecting upwardly from the top of the door structures and bearing upon the guides 12 above the doors. 70

On each of the journals 15 is affixed a ratchet wheel 20 above each of which are provided two pawls 21 and 22 on opposite sides of the journals 15, drawn into engagement with the ratchet wheel by 75 springs such as 23 connected with the pawls above their pivots. These pawls when in engagement with the ratchet wheel lock the journal against rotation and therefore lock the door against movement in either direction. The upper ends 24 and 25 of the pawls are extended upwardly alongside of a longitudinally movable horizontal rod 26 mounted in brackets 27 on which are affixed stops or pawl strips 28 and 29 outside of the 80 pawl extensions 24 and 25. 85

30 is a control lever pivoted at 31 and connected with rod 26 at 32. At the side of the hangar is a winch 33 having a rope drum 34. This winch may be reversible and 90 driven by a reversible electro-motor 35. 36 is a rope or cable running from one side of the winch drum to the adjacent lower corner of the door 14 to which it is detachably affixed. Another rope or cable 37 95 runs from the other side of the winch drum under a sheave 38 to the opposite lower corner of the door 14. Extensions 36^A and 37^A of the ropes 36 and 37 may be similarly connected with the lower corners of door 100 13, a sheave 38^A being provided for the rope extension 37^A.

When an electric motor is used to actuate the winch, a reversing switch 40 may be associated with the control lever 30 connected with the motor by suitable conductors as shown, so that when the lever is moved in one direction or the other, the motor will drive the winch in the desired direction. 105

The operation of this apparatus is as fol-

110

lows: when the control lever is in its central position, the door on which it is mounted will be locked against movement in either direction by the pawls 21-22. Now if the lever 30 on door 14 is moved to the right, the rod 26 will be moved in a corresponding direction, and all of the stops or pawl trips 28 thereon will move all of the pawls 21 out of engagement with their respecting ratchet wheels 20. The door 14 will then be released to be moved to the right but will be locked against movement in the opposite direction by the pawls 22. The door 14 may then be pulled over to the right 10 by the rope 36.

If two doors are used to close a structure such as the hangar shown, this will open half of the door opening. When the door 14 has reached the desired position the control lever is brought to its central position to allow the pawls 21 to again engage their respective ratchet wheels to lock the door against further movement. Now the control lever on door 13 may be moved to the left 20 and this door moved to the left by the extension of rope 36. By reversing these operations the doors may be closed.

When the winch is driven by a reversible electric motor 35 and reversing switches used 30 in connection with the control levers, a certain amount of lost motion may be provided so that the first movement of a control lever will release the pawls and a further movement of the control lever in the same direction 35 will close the motor circuits through the reversing switch to cause the motor to rotate the winch drawn in the direction to

move the door in the direction in which it is free to move. In bringing the lever back to its central position the motor circuits will first be broken at the reversing switch and then the released pawls permitted to engage their respective ratchet wheels.

This invention is shown applied to a pair of hangar doors of enormous size and weight 45 as it is particularly desirable for such structures. But it is obviously useful in connection with single doors or with doors of smaller size whether mounted to rest upon wheels as shown, or hung from wheels running upon overhead tracks. I do not therefore intend to limit myself to the particular form or construction shown and described, but in fact intend no limitations other than those imposed by the appended claim.

What I claim is:

A horizontally movable door, a heel for supporting the door, a latch for preventing the rotation of said wheel in one direction, another latch for preventing the rotation 60 of said wheel in the other direction, a motor for moving the door in either direction, a reversing switch for controlling the motor, and means actuated by the movement of said reversing switch in one direction for releasing one of said latches, and in the other direction for releasing the other latch.

In witness whereof, I have hereunto set my hand this 16th day of October, 1917.

CHARLES C. TOMKINSON.

Witnesses:

I. B. MOORE,
WILLIAM G. DALTON.
